CLAIM

The ornamental design for an earphone, as shown and described.

DESCRIPTION

FIG. 1 is a back perspective view of a first embodiment of an earphone showing our new design, the earphone of FIG. 1 is configured for use with a left ear of a user; FIG. 2 is a front perspective view thereof; FIG. 3 is a front view thereof; FIG. 4 is a back view thereof; FIG. 5 is a left side view thereof; FIG. 6 is a right side view thereof; FIG. 7 is a top view thereof; FIG. 8 is a bottom view thereof;

FIG. 9 is a back perspective view of a second embodiment thereof, the earphone of FIG. 9 is configured for use with a right ear of a user;

FIG. 10 is a front perspective view of FIG. 9;

FIG. 11 is a front view of FIG. 9;

FIG. 12 is a back view of FIG. 9;

FIG. 13 is a right side view of FIG. 9;

FIG. 14 is a left side view of FIG. 9;

FIG. 15 is a top view of FIG. 9; and,

FIG. 16 is a bottom view of FIG. 9.

The broken lines shown in the drawings are included for purposes of illustrating portions of the earphone and form no part of the claimed design.
